William Shaw, Albany, N. Y. Assignor to J. A. Melder, W. C. Bleeker & S. M. Rose
Letters Patent (Design No. 58) dated 10th July, 1846.

The schedule referred to in these Letters Patent and making
part of the same.

To all whom it may concern. Be it known that I, William Shaw of Albany in the County of Albany and State of New York, have invented or produced a new and ornamental design for a stove, and I do hereby declare that the following is a full, clear and exact description of the same, reference being had to the accompanying drawings making part of this specification, in which Fig. 1, represents a perspective view of a stove after my design; - Fig. 2 an enlarged view of the side, and Fig. 3, of the front. The figures forming the design are not easily described in words, but will be readily understood from the drawings - The oven door C - the end side door D, and the front door E, are bordered with a continuation of the figures shown at 2°, Figs. 2° & 3°. The border of flowers B B is carried entirely around

the oven doors, and across the front of the stove - The ornament at f.
is repeated in each corner of the hearth plate g and in the corners of the
hearth at h, k. - The figure bordering the hearth is shown at i.

What I claim as my invention is the combination
of ornamental figures herein described and shown forming an ornamental
design for a stove.
